CLAIM

The ornamental design for a container unit for needleless injector as shown and described.

DESCRIPTION

(21) Appl. No.: **29/805,670**

FIG. 1 is a front view of a container unit for needleless injector showing my new design;

(22) Filed: **Aug. 27, 2021**

FIG. 2 is a back view thereof;

(30) **Foreign Application Priority Data**

FIG. 3 is a right view thereof;

Nov. 26, 2018 (JP) D2018-025601

FIG. 4 is a left view thereof;

Nov. 26, 2018 (JP) D2018-025606

FIG. 5 is a top view thereof; and,

Nov. 26, 2018 (JP) D2018-025609

FIG. 6 is a bottom view thereof.

Nov. 26, 2018 (JP) D2018-025610

The broken lines shown in FIGS. 1-5 illustrate portions of the container unit for needleless injector that form no part of the claimed design.
